PYROPHORIC IGNITER

William J. Smith, Brooklyn, N. Y., assignor to
Ira Krivitzin, New Rochelle, N. Y.

Application July 12, 1934, Serial No. 734,759

3 Claims. (Cl. 67—7.1)

This invention relates to that class of lighters, now widely used, in which a rasp is supported in operative relation with a pyrophoric body in proximity to a wick tube and also in operative relation with actuating mechanism which, when operated by a spring or by hand, produces sparks from the pyrophoric body which ignite the combustible fluid supplied by the wick, all of these parts being mounted upon a reservoir, usually of small pocket size, which supplies the combustible fluid to the wick. The object of the invention is to improve the construction of such devices in various particulars to the end that there shall be provided a device of the kind referred to which shall be certain of operation under all conditions, shall be compact, shall not be liable to get out of order, shall effectually prevent evaporation of the fluid fuel when the device is not in use, shall be readily operated and shall in general be satisfactory to the user. The invention will be more fully explained hereinafter with reference to the accompanying drawing in which it is illustrated, and in which:

Figure 1 is a view in elevation of the improved igniter when closed and in readiness for use.

Figure 2 is a view of the same, partly in elevation and partly in vertical section, the parts being shown in the positions which they assume when they have been actuated and the wick ignited.

Figure 3 is a top plan view of the lighter, as shown in Figure 1, but with a portion broken away to show details of construction.

Figure 4 is a view in horizontal section on the plane indicated by the broken line 4—4 of Figure 2.

Figure 5 is a top view of the reservoir with the sparking device removed, and

Figure 6 is a view in perspective of the sparking device removed from the reservoir.

The reservoir *a* is of usual form, having a bottom plate *a*¹, provided with a filling plug *a*² to permit the filling and re-filling of the reservoir with fluid fuel, and having a top plate *a*³ which supports the wick tube *a*⁴, which may be threaded in place, has an aperture, as at *a*⁵, to receive the tube which carries the pyrophoric body and has a flat headed screw *a*⁶, raised somewhat from the top *a*³ to provide a convenient means for securing the sparking devices in place as hereinafter described. The sparking devices are carried by a bracket or frame which has two spaced walls or cheek pieces *b*¹ and a bottom plate *b*² which is formed with a keyhole slot *b*³, the larger part of which is of such size as to permit the entrance

of the head of the screw *a*⁶ which is thereafter engaged by a slight turning movement of the bracket or frame *b*, whereby the bracket or frame and the sparking devices carried thereby are retained securely in position and yet may be removed readily when necessary for purposes of inspection or repair.

The pyrophoric body *c* is spring supported within a tube *d* in which is placed a spring *d*¹, the tension of which may be adjusted by a knurled screw *d*² whereby the pyrophoric body is pressed upward against the rasp with yielding and adjustable pressure. The tube *d* is supported by a flanged head *d*³ which rests upon the top *a*³ of the reservoir and is enclosed within a tube *d*⁴ closed at its bottom and integrally united with the top *a*³ so that no fluid fuel may escape and so that the efficiency of the pyrophoric body shall not be lessened by the presence of the fluid fuel.

The head *d*³ is forked or provided with cheek pieces *d*⁵ between which is mounted on a spindle *e* the circular metal rasp *e*¹ against which the pyrophoric body *c* is pressed upward by the spring *d*¹. Upon the end of the spindle *e* is secured, as by a headed axial screw *e*², an arm *e*³. The latter is connected by a link *e*⁴ with a spring actuated carrier lever *e*⁵, which is mounted on an axis *e*⁶ between the cheek pieces *b*¹ of the bracket or frame *b*, a spring *e*⁷ being coiled about the axis *e*⁶ and bearing at its ends against the bottom plate *b*² of the bracket *b* and against the carrier lever *e*⁵, tending normally to throw the carrier lever *e*⁵ from the closed position shown in Figure 1 to the fully operated position shown in Figure 2.

The carrier lever *e*⁵ is held normally in the closed position shown in Figure 1 by a spring latch *f* which is mounted on the bottom plate *b*² of the bracket *b* and at its hooked free end normally engages a cross-pin *e*⁷ carried by the cheek pieces *e*⁸ which form the end of the carrier lever *e*⁵. In the cheek pieces *b*¹ of the bracket *b* is mounted a push-pin *f*¹ which carries a cone *f*² and at one end is provided with a push-button *f*³. The cone *f*² is so positioned with respect to the latch *f* that the spring latch *f* acts upon it to press the push-pin toward the observer, as in Figures 1 and 2, moving the push-button *f*³ away from the adjacent cheek piece, the latch then engaging the cross-pin *e*⁷ of the carrier lever *e*⁵ and holding the carrier lever *e*⁵ in closed position, as in Figure 1. When pressure is thereafter applied to the push-button *f*³ the cone *f*² acts upon the latch to disengage it from the cross-pin *e*⁷, thereby releasing the carrier lever *e*⁵ and permitting it to

be thrown from the closed position shown in Figure 1 to the open position shown in Figure 2.

The carrier lever e^5 supports at its free end a snuffer or extinguisher e^9 which, in the closed 5 position of the parts, as shown in Figure 1, fits down snugly upon the wick tube a^4 , extinguishing the flame at the end of the wick and preventing leakage or evaporation of the fluid fuel regardless of the position of the igniter.

- 10 The operation of the igniter will be readily understood. When the parts are in the position shown in Figure 1 pressure upon the push-button f^3 will release the spring actuated carrier lever e^5 , removing the extinguisher from the wick tube 15 e^1 and rotating with a quick movement the rasp e^1 and rotating with a quick movement the rasp e^1 in contact with the pyrophoric body c and causing sparks to be thrown upon the wick as it projects from the wick-tube and igniting the fluid fuel. As soon as the flame has served its purpose 20 the parts are returned from the open position shown in Figure 2 to the closed position shown in Figure 1 by pressure of the thumb upon the carrier lever e^5 .

It will be understood that changes in details 25 of construction and arrangement can be made to suit different conditions of use and that, except as pointed out in the accompanying claims, the invention is not restricted to the precise construction and arrangement shown and described 30 herein.

I claim as my invention:

1. In a pyrophoric igniter, the combination with a reservoir having a top plate supporting a wick tube and provided with a screw having its 35 head raised from said top plate, of a removable self-contained unit comprising a bracket having lateral walls and a bottom plate provided with a keyhole for engagement with said screw, sparking devices mounted upon said bracket, said devices comprising a tube carrying at one end thereof a pyrophoric body, means carried by said tube to exert a yielding pressure upon the pyrophoric body, said tube being supported by a flanged head 30 piece terminating in a fork, a circular metal rasp mounted on a spindle supported between said fork and secured in place by an axial screw, an arm extending therefrom, a carrier lever having 35 an arcuate arm and pivotally mounted on said bracket, a link connecting said arm with said carrier lever, a snuffer supported on the free end of said carrier arm, a wick projecting through said wick tube and in position to be covered by said snuffer, a spring coiled about the 40 axis of said carrier lever and bearing at its end against the bottom plate of the bracket and against the carrier lever so as to provide a tension tending normally to swing the carrier lever upwardly, a spring latch adapted to engage the carrier lever 45 and retain the parts in closed position, a push pin armed with a cone and normally positioned with respect to said latch so that the cone is disengaged therefrom whereby, in response to depression of said pin the latch is disengaged and the upward movement of said carrier arm uncovers the wick and said rasp is rotated against 50 said pyrophoric body.

2. In a pyrophoric igniter, the combination with a reservoir having a top plate supporting a wick tube and provided with a screw having its head raised from said top plate, of a removable self- 55

contained unit comprising a bracket having lateral walls and a bottom plate provided with a keyhole for engagement with said screw, sparking devices mounted upon said bracket, said devices comprising a tube carrying at one end thereof a pyrophoric body, a circular metal rasp rotatably mounted in a flanged head piece carried at the top of said tube, a carrier lever pivotally mounted on said bracket, an arm extending from said head piece and secured to said rasp, a link 10 connecting said arm with said carrier lever in the fashion of a toggle lever, resilient means for providing a tension tending normally to swing the carrier lever upwardly, a spring latch adapted to engage the lever and retain the parts in closed 15 position, and a push pin armed with a cone for cooperation with the spring latch to disengage the same from the lever.

3. In a pyrophoric igniter, the combination with a reservoir having a top plate supporting a wick tube and provided with a screw having its head raised from said top plate, of a removable unit comprising a bracket having two lateral walls and a bottom plate provided with a keyhole slot for engagement with said screw, sparking devices mounted upon said bracket, said devices comprising a tube carrying at one end thereof a pyrophoric body, means carried by said tube to exert a yielding pressure upon the pyrophoric body, said tube being supported by a flanged head 30 piece terminating in a fork, a circular metal rasp mounted on a spindle supported between said fork and secured in place by an axial screw, an arm extending therefrom, a carrier lever having 35 an arcuate arm and pivotally mounted on said bracket, a link connecting said arm with said carrier lever, a snuffer supported on the free end of said carrier arm, a wick projecting through said wick tube and in position to be covered by said snuffer, a spring coiled about the 40 axis of said carrier lever and bearing at its end against the bottom plate of the bracket and against the carrier lever so as to provide a tension tending normally to swing the carrier lever upwardly, a spring latch adapted to engage the carrier lever 45 and retain the parts in closed position, a push pin armed with a cone and normally positioned with respect to said latch so that the cone is disengaged therefrom whereby, in response to depression of said pin the latch is disengaged and the upward movement of said carrier arm uncovers the wick and said rasp is rotated against 50 said pyrophoric body.

WILLIAM J. SMITH. 55
